PROCESS FOR THE MANUFACTURE OF
BOOTS AND SHOES

Carl Behrens, Alfeld-on-the-Leine, Germany

Application May 21, 1932, Serial No. 612,697
In Great Britain May 21, 1931

1 Claim. (Cl. 12—145)

Heretofore, in the manufacture of boots and shoes, after fixing the insole to the bottom of the tacking last, the upper has been pulled over and its edges have been tacked or lasted round the edge of the insole. This lasting stretches the leather transversely across the last.

In the new process, stretching of the upper is effected by adjusting the length of the last, that is to say by stretching the leather in the longitudinal direction of the last. The lasting process employed heretofore is thereby eliminated and stretching no longer depends upon the feel of the workman but upon the magnitude of the elongation of the last during lasting and can therefore be proportioned most exactly.

A last to be employed for example in the new process is shown in the accompanying drawing.

According to the new process, the last is shortened somewhat, for example as shown, that is to say, the heel part is lifted by means of the screw-threaded spindle, the entire length of the last being thereby reduced. In this condition, the insole is first fixed in known manner on the sole of the last and the upper is likewise pulled over. Thereupon, the last is brought to the normal length by means of the screw-threaded spindle, that is to say, the heel portion is brought into the dotted line position whereby the leather is stretched on the last in the longitudinal di-

rection. Since leather is a material which, when it is elongated in one direction, becomes shorter in the transverse direction, this longitudinal elongation causes the upper to be pressed in all places against the last, the said upper being thereby given the correct shape. In this position, the upper is fixed to the insole.

It is clear that a very definite degree of stretching corresponds to a definite magnitude of the extension of the last for stretching, and that it is thus possible at any time to impart a definite stretch to the leather.

I claim:—

A process for manufacturing footwear which consists in fastening an insole and a vamp at the front and at the heel portion to a shoe-last adjustable in a longitudinal direction, after the last has been shortened, whereupon the leather, fastened on the last, is stretched with equal tension in all cross-sectional parts by a mutual sliding motion of the components of the last relative to each other and in a direction oblique to the longitudinal axis of the shoe-last, while at the same time the direction of the stress during the stretching is permanently changed, and uniting the insole with the vamp in this position throughout their whole length.

CARL BEHRENS.
